(57) **CLAIM**

The ornamental design for an axle holder for motorcycle, as shown and described.

DESCRIPTION

FIG. 1 is a front, left side, top perspective view showing our new design;

FIG. 2 is a front, right side, top perspective view thereof;

FIG. 3 is a front, left side, bottom perspective view thereof;

FIG. 4 is a front, right side, bottom perspective view thereof;

FIG. 5 is a rear, left side, top perspective view thereof;

FIG. 6 is a rear, right side, top perspective view thereof;

FIG. 7 is a rear, left side, bottom perspective view thereof;

FIG. 8 is a rear, right side, bottom perspective view thereof;

FIG. 9 is a front view thereof;

FIG. 10 is a rear view thereof;

FIG. 11 is a left side view thereof;

FIG. 12 is a right side view thereof;

FIG. 13 is a top plan view thereof;

FIG. 14 is a bottom plan view thereof;

FIG. 15 is a cross-sectional view thereof taken along at **15-15** of FIG. 9;

FIG. 16 is a cross-sectional view thereof taken along at **16-16** of FIG. 9;

FIG. 17 is a cross-sectional view thereof taken along at **17-17** of FIG. 9;

FIG. 18 is a cross-sectional view thereof taken along at **18-18** of FIG. 9;

FIG. 19 is a cross-sectional view thereof taken along at **19-19** of FIG. 11;

FIG. 20 is a cross-sectional view thereof taken along at **20-20** of FIG. 11; and,

FIG. 21 is a perspective view thereof in a state of use.

The broken line showing in the Figures represents portions of the axle holder for motorcycle that form no part of the claimed design.

The continuous lines in the Figures represent the opening of the axle holder for motorcycle and forms part of the claimed

(Continued)

design. The fine lines on the surface of the inside of the opening in each figure represent ridgelines that are curves of a solid surface.
